UNITED STATES PATENT OFFICE.

GEORGE LLOYD, OF CHICAGO, ILLINOIS, ASSIGNOR TO BENJAMIN HELLER AND ALBERT HELLER, OF CHICAGO, ILLINOIS, COPARTNERS.

DESIGN FOR A BOTTLE.

45,565.

Specification for Design.

Patented Apr. 7, 1914.

Application filed January 28, 1914. Serial No. 815,093. Term of patent 14 years.

To all whom it may concern:

Be it known that I, GEORGE LLOYD, a citizen of the United States, residing at Chicago, in the county of Cook and State of Illinois, have invented a new, original, and ornamental Design for Bottles, of which the following is a specification, reference being had to the accompanying drawing, forming a part thereof.

Figure 1 is a perspective view of the bottle showing principally the flat side. Fig. 2 is a view of the bottle in elevation showing the semi-cylindrical side. Fig. 3 is a top plan view of the bottle. Fig. 4 is a sectional view taken on line 4—4 of Figs. 1 and 2.

The design represents an approximately semi-circular bottle as disclosed more particularly by Figs. 3 and 4, the flat or plain side of which is provided with an inset or panel 10 while the semi-cylindrical or curved side is likewise provided with a panel 11 which extends throughout the greater por-

tion of such semi-cylindrical curvature. At the upper end the semi-cylindrical body is provided with a shoulder 12 above which the body curves inwardly as at 13 to a neck 14. The neck terminates at its upper end in a bead 15 and a stopper receiving extremity 16.

As seen from one side the bottle presents the appearance of a completely circular bottle while seen from the opposite side it presents the appearance of a flat paneled bottle. It is obvious, therefore, that by reversing the bottle two effects are produced which may be varied as found desirable in the sale or display of the goods packed in such a bottle.

I claim—

The new, original and ornamental design for bottles as shown and described.

GEORGE LLOYD.
